UNITED STATES PATENT OFFICE.

SIMON KENCHEN, OF NEW HAVEN, CONNECTICUT.

VULCANIZER.

1,342,916.

Specification of Letters Patent.

Patented June 8, 1920.

Application filed December 16, 1919. Serial No. 345,339.

To all whom it may concern:

Be it known that I, SIMON KENCHEN, a subject of the Government ruling Lithuania, and a resident of New Haven, in the 5 county of New Haven and State of Connecticut, have invented a new and Improved Vulcanizer, of which the following is a specification.

My invention relates more especially to a 10 vulcanizer adapted for the repair of devices that are easily handled, as the inner tubes of vehicle tires and similar devices, and an object of my invention, among others, is to provide a device of this class 15 that shall be simple in its construction and particularly efficient in its operation.

One form of device embodying my invention and in the construction and use of which the objects herein set out, as well as 20 others, may be attained, is illustrated in the accompanying drawings, in which—

Figure 1 is a plan view of a vulcanizer embodying my invention, partially cut away in central section to show construction.

Fig. 2 is a view in side elevation with parts cut away in central section to show construction.

Fig. 3 is a view in cross section, scale enlarged, on plane denoted by dotted line 3—3 of Fig. 2.

In the accompanying drawings the numeral 5 indicates a rest, preferably in the form of a plate, with a shank 6 connecting 35 the rest with a stem 7. A lug 8 on this stem is received within a slot in the end of the shank 9 of a forked clamp support 10 between the prongs of which support a receptacle clamp 11 is pivotally mounted.

40 This receptacle comprises a cover 12 secured in place in any desired manner and having a flange 13 depending within the receptacle and providing an opening 14 of considerable size extending through the cover at

45 the center thereof.

A reservoir 15, in the form of a tube encircling the flange, is located within the cover, as clearly shown in Fig. 2 of the drawings, this reservoir having a filling 50 orifice closed by a spring seated valve 16. The under side of the reservoir is provided with minute openings for the outflow of some inflammable substance, as gasoline.

The receptacle 11, in the form of a cup, 55 has prongs 17 projecting upwardly from the bottom thereof, these prongs being fas-

tened to a prong supporting disk 18 located in the bottom of the receptacle. An absorbing material, as a sheet 19 of asbestos, is located at the bottom of the receptacle, 60 upon the disk 18, and a screen 20, preferably of wire mesh, is located on this absorbent sheet, the prongs 17 projecting upwardly through the sheet of absorbent material and through the meshes of the wire 65 screen.

The stem 7 is threaded to fit a threaded opening in an actuating sleeve 21, the latter being connected by a sleeve 22 with a clamp sleeve 23. Tongues 24 extend from the 70 clamp sleeve into grooves 25 in opposite sides of the stem 7, these tongues being formed by bending portions of the metal comprising the sleeve inwardly.

The method of use of the device will be 75 readily understood, it being briefly stated that a heating medium, as gasoline, is placed within the reservoir 15 and the article, as an inner tube supplied with a patch to be vulcanized, is placed upon the rest 80. The sleeve 21 being turned the clamp sleeve 23 is pushed into engagement with the shank 9 of the clamp forcing the latter tightly against the article on the rest 5. The absorbent sheet 19 having been saturated 85 with gasoline from the reservoir, a flame being applied thereto will cause the article to be heated sufficiently for vulcanizing purposes, the structure providing means where by just a sufficient amount of fuel will be 90 supplied for this purpose.

In accordance with the provisions of the patent statutes I have described the principles of operation of my invention, together with the device which I now consider to represent the best embodiment thereof; but I desire to have it understood that the device shown is only illustrative and that the invention may be carried out by other means.

100 I claim—

1. A vulcanizer comprising a rest and a heating member movably connected and normally extending in divergent directions, a stem rigidly connected with one of said 105 members, an operating sleeve having a feeding connection with said stem, and a clamp sleeve co-operatively connected to said operating sleeve to move said members together.

2. A vulcanizer comprising a rest and a 110 heating member pivotally connected and normally extending in divergent directions,

a stem rigidly connected with one of said members, an operating sleeve having a threaded connection with said stem, and a clamp sleeve coöperatively connected to said operating sleeve to move said members together.

3. A vulcanizer comprising a rest and a heating member movably connected and normally extending in divergent directions, a stem rigidly connected with one of said members, an operating sleeve having a feeding connection with said stem, a clamp sleeve longitudinally movable on said stem, means for holding it against rotation thereon, and an operative connection between said sleeves.

4. A vulcanizer comprising a rest and a heating member movably connected and normally extending in divergent directions, a stem rigidly connected with one of said members, said stem having a longitudinal groove therein, an operating sleeve having a feeding connection with said stem, a clamp sleeve longitudinally movable on the stem, a lug inturned from said clamp sleeve into said groove to hold the sleeve against rotation on the stem, and a coöperative connection between said sleeves.

5. A vulcanizer comprising a rest and a heating member movably connected and normally extending in divergent directions, a stem rigidly connected with one of said members, an operating sleeve having a feeding connection with said stem, a clamp sleeve longitudinally movable on the stem, means for holding the clamp sleeve against rotation on the stem, and a connecting sleeve having a lip engaging a groove in one of said members.

40 6. A vulcanizer comprising a rest and a forked heating member support movably connected and normally extending in divergent directions, a stem rigidly connected with one of said members, an operating

sleeve having a feeding connection with said stem, a clamp sleeve coöperatively connected to said operating sleeve to move said rest and heating member together, and a clamp and heating member pivotally supported between the prongs of said fork.

50 7. A vulcanizer including a rest and a heating member, the latter comprising an inclosed receptacle, a tube arranged within said receptacle to receive a heating medium, said tube being provided with means to permit flow of the heating medium into the receptacle, and means for forcing said rest and heating member toward each other.

8. A vulcanizer including a rest and a heating member, the latter comprising a receptacle, a cover for said receptacle, said cover having a depending flange, a tube to receive a heating medium and surrounding said flange, said tube being provided with means to permit flow of the heating medium into the receptacle, and means for forcing the rest and heating member toward each other.

60 9. A vulcanizer including a rest and a heating member, the latter comprising an inclosed receptacle, an absorbent uninflammable material located in the bottom of the receptacle, a screen overlying said material, a cover for the receptacle, a flange depending from the cover, a tube surrounding said flange and having means to permit flow of inflammable material therefrom, and means for forcing said rest and heating member toward each other.

70 10. A vulcanizer comprising a rest and a heating member movably connected and normally extending in divergent directions, a stem rigidly connected with one of said members, a clamp sleeve mounted on the stem, and means for operating said clamp sleeve.

SIMON KENCHEN.
